UNITED STATES PATENT OFFICE.

HENRY K. SHANCK, OF CLEVELAND, OHIO.

EXPLOSIVE-ENGINE.

No. 813,746.

Specification of Letters Patent.

Patented Feb. 27, 1906.

Application filed July 20, 1903. Serial No. 166,233.

To all whom it may concern:

Be it known that I, HENRY K. SHANCK, a citizen of the United States, and a resident of Cleveland, county of Cuyahoga, State of Ohio, have invented certain new and useful Improvements in Explosive-Engines, of which I hereby declare the following to be a full, clear, and exact description, such as will enable others skilled in the art to which it appertains to make and use the same.

My invention relates to improvements in explosive-engines in which some one of the volatile products of hydrocarbon oil, as naphtha or gasolene, is employed as motive power when commingled with the requisite proportion of air in the cylinder.

The objects of the invention are, primarily, to obtain a more perfect admixture of the hydrocarbon gas and air before entering the cylinder, to insure a speedy and complete exhaustion thereof from the cylinder, and to provide a form of spraying device for the motive fluid and intermediate gas-and-air reservoir or chamber by means of which it is more thoroughly condensed and commingled with the air and in condition for immediate use in the cylinder—a further object of great importance.

My invention further consists in the combination and arrangement of parts and construction of details, as hereinafter described, shown in the accompanying drawings, and specifically pointed out in the claims.

In the accompanying drawings, Figure 1 is a side elevation of the complete device, showing the various connections of the engine with the feeding device, fuel-reservoir, air-pressure chamber, filter, pump, and safety-valve, the pump, filter, and safety-valve being shown in vertical central section. Fig. 2 is a plan view of the same. Fig. 3 is an enlarged plan of the engine alone. Fig. 4 is a vertical longitudinal section on center line of one of the engine-cylinders, showing inlet and commingling chambers also in section. Fig. 5 is a transverse section through double cylinder, compressing-chambers, and partial longitudinal section through the inlet-chamber which bridges over the two compression-chambers of the engine. Fig. 6 is a longitudinal section of the spraying valve and tube which enters the inlet-chamber centrally between the two cylinders. Fig. 7 is a longitudinal section of one of the cylinders, showing the admission and exhaust openings uncovered by the piston and illustrating the action

of the deflector in driving out the consumed gas.

In the figures, 1 are the cylinders of a twin-cylinder engine; 2, the piston of each engine; 3, the piston-rods, and 4 the cross-heads. Each cylinder is provided with tight cylinder-heads 5 at either end and on the upper side with an inlet-port 6, arranged transversely through the shell to admit the commingled air and gas behind the piston. This is placed approximately in a central position between the cylinder-heads. At the front of the cylinder and also on the upper side close to the cylinder-head is a second port 7, through which the commingled air and gas to be compressed is drawn into the cylinder in front of the piston. The exhaust-port is seen at 8 at the lower side of the cylinder and opposite to the admission-port, but in advance thereof, the forward edge of the exhaust-port being vertically underneath the rear edge of the admission-port above. The exhaust-port is large enough to give an easy exhaust and is so placed in order to permit the exhaust to commence in advance of the admission on the forward stroke of the piston and to continue during the admission, so that the spent gases may be thoroughly driven out by those freshly entering the cylinder, thus obtaining a greater power of explosion, since the entire charge is pure, than could be obtained if vitiating gases were mingled with pure gas. To greatly assist in this operation, the upwardly and rearwardly extending lip or flange 9 is secured to the back of the piston. This deflector turns the pure gas toward the upper rear extremity of the cylinder, as seen in Fig. 7, whence it circles about the end of the cylinder and quickly drives out the vitiating gas through the exhaust-port 8, thus filling the cylinder much more quickly with pure gas and thoroughly cleansing it of the spent gas.

In order to obtain a thoroughly-commingled supply of air and gas to the cylinder and also to supply it under compression, the following form of construction is employed: 10 is the reservoir in which the motive fluid is stored. 11 is the pipe leading therefrom to the filter 12, by means of which impurities in the oil are prevented from entering the pump or valve and interfering with its action. 13 is the pump, by means of which a constant stream of oil is supplied to the equalizing-chamber 14, which is filled with air compressed as the oil enters the chamber, thus maintaining a steady even degree of pressure

- thereon. 15 is the spraying-tube, into which the oil is next in turn received, and 16 is the valve at the outer end of this tube, by means of which the stream of oil under pressure is finely vaporized and in the form of mist is projected into the spraying-tube. In this tube openings 17 admit the air, which is drawn into the tube by the suction of the piston in the cylinder. There being two cylinders, a chamber 18 bridges them and receives the jet of commingled air and gas and retains the mixture until drawn into the final commingling and compressing chambers 9 and cylinders below. A safety-valve 35 returns the oil, if the pressure becomes too great, to the reservoir 10. The construction and use of these chambers and intermediate valves may be described as follows: The cylinders being alike the description of one will serve for both.
- As the piston travels backward it sucks down the mixture of gas and air from the bridge-chamber through the valve 20, the tension upon which is controlled by means of the spring 21 encircling its stem 22. By this means the chamber 19 is filled with the explosive mixture, which is further drawn into the engine-cylinder through the port 7. When at the end of the piston-stroke, the chamber 18 and cylinder are both filled with the mixture and the piston begins to move forward, the suction thereof ceases; and the valve 20 closes to stop the entrance of more of the gaseous mixture. The compression of the gas in the chamber 19 then commences and continues until the piston ceases its forward movement, the size of the chamber 19 being so proportioned in relation to the cylinder as to receive and hold the requisite amount of the compressed explosive at the required degree of density to serve as one charge for the cylinder. In this manner each charge can be mathematically portioned out without waste or variation in density. It will readily be seen that since a short period of time must elapse during the process of compression in the cylinder and chamber and in the bridging-chamber before the valve opens to admit the mixture to the compression-chamber there will be given an opportunity for the atoms of air and gas to combine and form a homogeneous mixture of even quality throughout which will be in condition for immediate use in the cylinder and will simultaneously explode through all its parts.
- In a single engine the bridge of course would be unnecessary, and only one valve would be required and one end of the chamber only would be needed.
- A very important feature of the invention is found in the construction of the vaporizing-tube, as shown in Fig. 6. Here 25 is the valve-stem, slightly flattened on the sides, so as to afford passage to the fluid, and conical at 26 to engage the conical seat 27. The inner extremity of the valve is cylindrically reduced at 28 and loosely passes through the opening 29 in the seat. This cylindrical stem compels the jet to take a longitudinal direction and prevents any cross-currents, such as are generally found in taper needle-valves when not well centered. In order to project the finely-sprayed or mist-like fluid through the tube in parallel lines, so that it will be mingled with and completely taken up by the air entering the openings 17, the admission-opening is made with parabolically-curved sides, as seen at 31. The effect of this is to project the mist longitudinally of the tube as fast as it is atomized by the valve. In this manner the air and gas being propelled together through the tube into the bridge-chamber a much more intimate commingling thereof can be obtained than in any other way.
- Having described my invention, what I claim as new, and desire to secure by Letters Patent, is—
1. In a twin-cylinder explosive-engine, the combination with the cylinders having closed ends, of duplicate compression-chambers independently mounted thereon and of predetermined less capacity than the cylinders therefor, each provided with a passage communicating with the front of its respective cylinder, an admission-port from each compression-chamber centrally placed in each cylinder between its ends, an exhaust-port for each cylinder arranged to exhaust in advance of the admission, a commingling-chamber arranged to bridge the compression-chambers, duplicate passages between the condensing-chambers and the bridge-chamber, automatic valves therein, an elongated spraying-tube entering the bridge-chamber between the compression-chambers, a valve at the outer end of the tube, air-inlets therefor, and a delivery-nozzle for the valve adapted to discharge vapor longitudinally of the tube, substantially as described.
  2. In an explosive-engine, the combination with duplicate cylinders closed at both ends and duplicate pistons therein, of duplicate compression-chambers mounted thereon, of pronounced smaller capacity than the cylinders, duplicate passages at the forward ends of the cylinders connecting them with the compression-chambers, exhaust-ports arranged to exhaust in advance of the admission, admission-ports placed centrally of the cylinders communicating with the compression-chambers, duplicate deflectors curving upwardly and rearwardly from the backs of the pistons, a bridge-chamber connecting the compression-chambers, a spraying-tube inserted in said bridge-chamber, and duplicate valves and admission-ports between the bridge-chamber and compression-chambers, substantially as set forth.
  3. A twin gas-engine comprising twin cylinders, pistons, duplicate independent compression-chambers mounted upon the cylinder.

ders and of pronounced smaller diameter than the cylinders, a bridge-chamber connecting the compression-chambers, automatic valves in said bridge-chamber communicating with the compression-chambers, and a horizontal spraying-tube communicating centrally with said bridge-chamber.

In testimony whereof I hereunto set my hand this 10th day of July, 1903.

HENRY K. SHANCK.
